UNITED STATES PATENT OFFICE.

JOHN ABNER WEITZEL, OF FALL BROOK, CALIFORNIA.

TAG-HOLDER.

1,034,403.

Specification of Letters Patent. Patented July 30, 1912.

Application filed April 5, 1911. Serial No. 619,189.

To all whom it may concern:

Be it known that I, JOHN A. WEITZEL, a citizen of the United States, residing at Fall Brook, in the county of San Diego and State of California, have invented a new and useful Tag-Holder, of which the following is a specification.

This invention relates to a tag holder particularly intended and adapted for holding the price mark tags for merchandise, the tag holder being, for example, adapted to be placed on the shelves holding the merchandise and to hold the tag exposed to the view at the front of the shelves.

15 The main object of the present invention is to provide a tag holder of simple and cheap construction adapted to hold the tag or price card in such manner as to expose the same to view and to enable ready substitution or replacement of the card or tag.

Another object of the invention is to provide a tag holder which will protect the tag or card from dust while exposing the same to view.

25 Other objects of the invention will appear hereinafter.

The accompanying drawings illustrate the invention, and referring thereto:

Figure 1 is a perspective view of a portion of a shelf with the tag holder in place thereon. Fig. 2 is a perspective view of the tag holder in process of manufacture, the members thereof being in separated position. Fig. 3 is a perspective view of the 30 card or tag. Fig. 4 is a section on line x^4-x^4 Fig. 1, showing the tag holder with the card therein. Fig. 5 is a view similar to Fig. 4, showing the card partly withdrawn. Fig. 6 is a horizontal section on line x^6-x^6 in Fig. 4.

The tag holder comprises a flat body 1 formed of suitable thin malleable material, for example, sheet metal, and having a depending lip or flange 2 of the same width as 45 the flat body at its forward end, said lip or flange extending at right angles to said body, and a transparent front plate 3 secured on said lip and adapted to hold the tag, indicated at 4, in position between said 50 front plate and said body.

The front plate 3 may consist of sheet celluloid or similar transparent material capable of being folded and said plate is folded inwardly at its ends, as indicated at 55 5, to extend around and back of the ends of the lip or flange 2 beneath the flat body 1 and

said lip or flange 2 is provided at its lower edge with prongs or projections 6 adapted to be bent up under the front plate 3 to retain the same in place, as indicated in Figs. 1, 4 and 5. The celluloid front plate 3 has more or less elasticity enabling it to yieldingly hold itself close to the lip or flange 2 by engagement with the ends of said lip or flange, leaving, however, sufficient space between said front plate and lip for insertion of the card 4. To insure this spring action of the front plate, the end portions 5 thereof are preferably bent in the form of a roll or indent curve, so as to engage with the back of the flange 2. Said card or tag 4 may be of cardboard and provided with marks or indications for the prices or other desired data. The lip or flange 2 is formed with an opening or perforation 8 of sufficient size to enable the tip of a finger to be inserted through said opening into engagement with the back of the card 4 for pushing the said card upwardly out of the pocket between the front plate and the lip or flange.

The device is assembled as follows: The body 1 having been formed with a depending lip or flange 2, having an opening or hole 8 and projections 6, said projections extending in the plane of the flange, the transparent front plate 3 is pushed up onto said flange and engages by its folded end portions 5 with the ends of the flange 2 and when the front plate has been pushed directly in front of the flange, as shown in Fig. 4, the prongs 6 are bent up, as shown in said figure, to engage beneath said front plate and hold the same in position. When the front plate 3 is in position the folded end portions extend beneath the flat body so as to limit its upward movement when the tag is removed. The card 4 may then be inserted and the tag holder placed on the shelf, as indicated in Fig. 1. If it is desired to change the card at any time, the tag holder is withdrawn from the shelf, the tip of the finger inserted through the opening 8 and brought into contact with the card or tag and pushed upwardly so as to eject the tag from the holder, whereupon a new card may be inserted.

When the card is placed in the space between the front plate and the flange 2, it rests at its lower edge on the prongs or projections 6, said prongs supporting the card as well as the front plate. Said prongs extend up in front of the transparent front

plate at the lower edge thereof so as to hold said front plate from springing outwardly and to furnish a support for the front plate when the pressure is brought upon the card 5 by the insertion of the finger through the opening 8 in the ejection of the card.

What I claim is:

A tag holder comprising a thin flat body formed in one piece with a flange bent at 10 right angles thereto, having a finger tip opening and upturned front prongs, at its lower edge, providing tag supporting hooks, and a resilient transparent front plate supported on the prongs and having inwardly 15 folded end portions embracing the ends of

the flange beneath the body so as to limit the upward movement of the front plate when the tag is removed; the inbent edges of the folded end portions bearing yieldingly against the rear side of the flange so 20 as to press and hold the tag firmly between the flange and the front plate while permitting the ready removal of the tag.

In testimony whereof, I have hereunto set my hand at Fall Brook, California, this 25 14th day of March, 1911.

JOHN ABNER WEITZEL.
